UNITED STATES PATENT OFFICE.

NICHOLAS OKLER, OF AURORA, ILLINOIS.

RAIL-JOINT.

1,241,653.

Specification of Letters Patent.

Patented Oct. 2, 1917.

Application filed May 8, 1916. Serial No. 96,006.

To all whom it may concern:

Be it known that I, NICHOLAS OKLER, a citizen of the United States of America, and resident of Aurora, Kane county, Illinois, have invented a certain new and useful Improvement in Rail-Joints, of which the following is a specification.

My invention relates to improvements in rail chairs or rail joints, and one of the objects of my invention is to provide an improved structure of this character which will be simple, durable and reliable in construction, effective and efficient in operation and inexpensive to manufacture.

Another object of my invention is to eliminate the numerous bolts and nuts which are commonly used in rail joints and thus eliminate the expense of maintenance and the danger of loose joints consequent upon the use of bolts and nuts.

Another object of my invention is to provide an improved structure which can easily be installed by an unskilled workman and which will after being installed require very little, if any, maintenance.

Other objects of my invention will appear hereinafter.

My invention consists in the features of novelty exemplified in the construction, combination and arrangement of parts hereinafter described, shown in the accompanying drawing and more particularly set forth in the appended claims.

Referring to the drawing:

Figure 1 is a top plan view of a rail joint or chair involving my invention, the ball of the rail being removed on the section line 1—1 of Fig. 2 to more clearly disclose the parts therebelow;

Fig. 2 is a view in side elevation of the structure shown in Fig. 1;

Fig. 3 is an enlarged transverse section through the rail and joint on the line 3—3 of Fig. 1;

Fig. 4 is an enlarged detail section on the line 4—4 of Fig. 1; and

Fig. 5 is a detail section on the line 5—5 of Fig. 1.

In the drawings I have shown two sections A and B of rail, the abutting end portions of which are arranged to be held in proper relation by a rail chair or joint involving my invention. The head or ball of the rail section is represented at A¹, the web portions at A², and the base portions at A³. The structure which I have shown

and which embodies my invention is preferably composed of two sections or members C and D which are identical in construction and which when placed in position are 60 preferably of sufficient total length to span two of the ties E which are usual and ordinary in railway track construction. Each of these sections has a base or foundation plate 1 which rests flat upon the ties and 65 upon which the bases or flanges of the rail sections are solidly and firmly positioned. The entire base plate which is made up of two sections C and D placed together, forms a substantially flat rectangular construction. 70 The dividing line between the two base plate sections is centrally located with respect to the length of the structure, but this dividing line takes the form of a Z as shown in dotted lines in Fig. 1. This dividing line 75 has two parallel portions 3 and 4 which are disposed out of alignment with each other, and a connecting or middle portion 5 disposed substantially at right angles to the portions 3 and 4, this dividing line being 80 formed by the adjacent edges of the base plate sections. The edges of the base plate sections forming the dividing line portions 3 and 4 are correspondingly beveled as shown more clearly in Fig. 5, but the bevel 85 of the edges on the line 3 is opposite to that of the edges on the line 4. In consequence of which the base plate sections are, in a sense, positively interlocked against displacement out of the same plane but at the 90 same time permit a ready separation of the sections by a longitudinal movement of the sections away from each other. The edges of the base plate sections forming the right angled connecting portion 5 of the dividing 95 line, however, merely form a butt joint and are not beveled. There is a slight clearance between the beveled edges on the line portions 3 and 4 whereas the edges on the connecting line portion 5 abut, hence any force 100 applied longitudinally to the sections C and D of the structure to move the sections toward each other operates to exert a transverse force which I utilize to cause the sections C and D to tightly grip the rail sections and will be later described. This transverse or gripping force is brought about by the action of the edges of the base plate sections forming the angled connecting portion 5 of the dividing line. In other 110 words, these edges at the connecting portion 5 act, because of their angular relation

to force the base plate sections laterally with respect to the rail. On each side of the rail I provide gripping or clamping members or cheek plates A⁵ and B⁵. These members substantially conform to the angle between the web and base of the rail having the vertical portions 6 and horizontal portions 7. These vertical portions and horizontal portions of the gripping members are preferably integrally formed and in order to avoid an excess quantity of metal and still secure the maximum strength they are pressed in rigid relation with the integral webs 8. Each of the gripping members A⁵ and B⁵ is as long as the entire joint structure but each gripping member is secured to only one of the base plate sections for a portion of its length. Thus as shown in Figs. 1 and 3 the gripping member A⁵ is integrally formed as a part of the base plate section 1, this being joined to the face plate section on the outer edge thereof. In like manner the gripping member B⁵ is integrally joined along the outer edge of the base plate section 2. The projecting end of each gripping member A⁵ and B⁵ has the edge 7^a of its portion 7 tapered longitudinally which is adapted to co-operate with the corresponding edge 7^b of an upper standing flange or wedge member 9 of the other base plate section. Thus when the base plate sections are forced longitudinally toward each other they carry with them their corresponding clamping or gripping members, and the edges 7^a and 7^b operate as wedges to force the gripping members laterally toward each other and into gripping engagement with the rail. Since these wedges and both ends of the structure are identical the action thereof will be identical at both ends so far as the gripping of the rail is concerned. As a further precaution against any chance of relative displacement of the edges 7^a and 7^b with respect to each other, they are also beveled or undercut as shown clearly in Fig. 5. It is thus seen that when a joint in the rail is to be made the two ends of the rail sections are abutted together with the rail sections in alinement and the two sections C and D of the chair structure are placed in proper relative position with their wedges 7^a and 7^b in engagement. The sections C and D are then driven by a sledge hammer or other suitable instrument longitudinally toward each other until they are tightly inter-wedged and inter-locked, so to speak. By reason of the several wedge actions heretofore described the gripping members will be forced into extremely firm frictional engagement with the rail sections and tightly hold the rail sections in place. As a precaution against the loosening of the sections C and D with respect to each other, and to the rail sections, I provide a locking arrangement. By

reference to the drawing, and particularly to Fig. 4, it will be seen that the horizontal portion 7 of the gripping members has a spike hole 10 and the base plate is also provided with a spike hole 11. As shown clearly in Fig. 4, these holes are adapted to almost register when the sections C and D have been driven together as tightly as possible. By driving a spike 12 down through the holes 10 and 11 and into the tie the action of the spike on the walls of the holes 10 and 11 tends to draw the sections C and D still farther into engagement. The spikes 12 thus lock the plates against any retrogressive or loosening movement and by constructing the holes 10 and 11 of the proper size and in proper relation as shown in Fig. 4 the driving of the spike serves to further draw the sections C and D toward each other. I prefer that the gripping members actually engage and grip the rail on its web just beneath the head or ball of the rail. For this reason I provide a slight clearance 13 between the rail and the gripping members, as shown in Fig. 3, except at the upper portion of the gripping members. This clearance, of course in the drawing is exaggerated but it should be just sufficient so that the gripping action of the gripping members begins along the upper edge thereof just beneath the ball of the rail to increase the strength of these gripping members. At these points they are enlarged or thickened as shown clearly in Fig. 3. It will be noted also by reference to Fig. 1 that the upper edges or gripping faces 14 of the gripping members are curved longitudinally so as to provide a slight graduating clearance from the center to the ends of the gripping members. In the drawing this clearance is extremely exaggerated merely for the purpose of explanation but it should be just such that the gripping action on the rails begins, so to speak, at the end portions of the gripping members adjacent the wedges. The spring or elasticity of the metal operates to permit the central portions of the gripping members to exert a gripping action upon the rail, and this force is applied to the gripping members at their central portions by the action of the central wedge formed by the abutting edges of the base plate sections on the dividing line 5. It will thus be seen that I have entirely dispensed with the necessity of bolts and nuts for clamping the ordinary so-called fish plates to the rails, and I have also dispensed with the necessity of boring bolt holes in the end portions of the rail sections. At the same time I have employed a powerful gripping mechanism which will just as effectively retain the rail section in place and will, because of the fact that longitudinal movement of the rails will have no effect upon 130

the gripping action permit of the expansion and contraction of the rails during the various seasons without in any way loosening the joint. After the joint has been assembled and locked by the spikes 12 the entire structure may then be firmly fastened to the ties E by means of additional spikes 15 in the ordinary manner. The wedge portions 9 at the side edges of the base plate 5 sections are further strengthened by ribs or webs 9^a preferably formed integral with the structure. It will be noted also that the entire joint structure is made up of only two pieces of metal, each section or 10 piece C and D having all of its parts cast integrally.

I claim:

1. In a rail joint of the class described, the combination of a base plate comprising a seat for the rail and divided into two sections, on an angularly disposed line providing a wedge action between the two sections and operating to force the sections toward the rail when said sections are moved longitudinally, a clamping member formed on each section of said base plate and extending along the web of the rail, and having a wedge surface adjacent one end, a co-operating wedge surface on the other section of the base plate, said wedge portion being operable to force the clamping members in engagement with the web of the rail when the base plate sections are forced longitudinally of each other.
2. In a rail joint, the combination of a base member divided on an irregular line into two divisions, portions of the edges of said divisions being beveled in opposite direction to form an interlock to prevent relative displacement of the sections, a wedge member on each base plate division on the side of the rail opposite to that on the other base plate division, a clamping member formed integral with each base plate division and having a wedge portion adapted to co-operate with the wedge portion of the other base plate division whereby to grip the rail between said clamping members, said clamping members having gripping surfaces formed to grip the rails at the end portions thereof.

the rail between said clamping members, and means for locking the base plate divisions against retrogressive movement. 50

3. In a rail joint, the combination of a base member divided on an irregular line into two divisions, portions of the edges of said divisions being beveled in opposite direction to form an interlock to prevent relative displacement of the sections, a wedge member on each base plate division on the side of the rail opposite to that on the other base plate division, a clamping member formed integral with each base plate division 55 and having a wedge portion adapted to co-operate with the wedge portion of the other base plate division whereby to grip the rail between said clamping members, said clamping members having gripping surfaces 60 formed to grip the rails at the end portions thereof.

4. In a rail joint, the combination of a pair of rail web gripping members disposed on opposite sides of the rail web and having 70 their gripping faces formed to grip the rail web at the end portions initially of said gripping members and then gradually the other portions toward the center thereof by the spring of the material, a base member 75 for each gripping member having a wedge surface co-operating with a like wedge surface of the other member at substantially the central portion of the joint and operating to bring the central portions of the gripping members against the rail web, a wedge portion formed at the end of each gripping member arranged to co-operate with a wedge portion formed at the end of the base member of the other gripping member and operating to force the end portions of said gripping members into engagement with the rail. 80

Signed by me at Chicago, Illinois, this 4th day of May, 1916.

NICHOLAS OKLER.
